UNITED STATES PATENT OFFICE.

THOMAS B. JARVIES, OF KANSAS CITY, MISSOURI.

GAS HEATING APPARATUS.

No. 926,692.

Specification of Letters Patent.

Patented June 29, 1908.

Application filed November 9, 1907. Serial No. 401,431.

To all whom it may concern:

Be it known that I, THOMAS B. JARVIES, a citizen of the United States, residing at Kansas City, in the county of Jackson and State 5 of Missouri, have invented certain new and useful Improvements in Gas Heating Apparatus; and I do declare the following to be a full, clear, and exact description of the invention, such as will enable others skilled in the 10 art to which it appertains to make and use the same, reference being had to the accompanying drawings, and to the figures of reference marked thereon, which form a part of this specification.

15 My invention relates to gas heating apparatus, and more particularly to an apparatus of that class for use in combination with a hot air furnace.

It is the object of my invention to secure, 20 as nearly as possible, a perfect combustion of the burning fuel, and to provide an arrangement of parts which will not only secure such combustion, but will also so dispose the heat as to secure the best results therefrom.

25 A further object is to provide the improved details of structure which will presently be fully described and pointed out in the claims, reference being had to the accompanying drawings forming part of this specification, 30 in which like reference numerals refer to like parts throughout the several views, and in which:—

Figure I is a view, in side elevation, of a furnace equipped with an apparatus constructed according to my invention. Fig. II is a central, vertical, sectional view of same. Fig. III is a horizontal sectional view on the line III—III, Fig. II. Fig. IV is an enlarged detail view, in front elevation, of the furnace grate, burner, and fuel supply parts. Fig. V is an enlarged detail view, in side elevation, of one of the burners and mixing chambers. Fig. VI is a front view of similar parts, in central vertical section.

45 Referring more in detail to the parts:—1 designates the outer casing of a hot air furnace, of any ordinary construction, which is provided with the usual feed door 2, and an opening 3 to the ash pit.

50 Within casing 1 is a fire pot 4, preferably of cast iron, from which is suspended a grate 5, having side and bottom slots 6. Opening from the fire pot, near the top, and projecting through casing 1, is the smoke pipe 7; and 55 opening from the air chamber between the fire pot and casing, are the heat conducting

pipes 8, which may lead to apartments in the building within which they are located. Leading from a suitable fuel supply, (not shown) is a feed pipe 9, which projects into 60 casing 1 beneath grate 5, and is provided with an end cap 10. Leading from the main feed pipe 9 are branches 11, of any suitable number, which are turned upwardly at their ends and project through the bottom of the 65 grate, through the slots 6 if desired, and terminate slightly above the level of the tops of the slots in the sides of grate 5. Branches 11 are provided with the mixing chambers 12, preferably located below the grate bottom, 70 through which air is admitted to the branch pipes, for the purpose of providing a combustible fuel mixture.

13 designates a diaphragm which fits within the grate, preferably above the side slots, 75 and having perforations through which the upper ends of branches 11 project. On the upper end of each of branches 11 is a flame spreading hood, comprising a body portion 14, having a channel of slightly greater 80 diameter than that of said branches, and an inturned flange 15 which surrounds the fuel vent 16. Projecting upwardly from near the edge of the hood top is a baffle plate 17, which is inclined forwardly over the fuel vent, and 85 flares laterally as indicated in the drawing.

18 designates a base flange, preferably integral with the hood, which is adapted to rest on the diaphragm 13 when the hood is in position on the branch end.

When installing, the fuel feed pipe is connected with the furnace and the individual burner branches projected through the bottom of the grate, as described. The diaphragm 13 is then inserted in the grate and 95 adjusted so that the portions of the branches projecting thereabove will be of sufficient height to enable the ends of the pipes to rest against the inturned hood flange, and the hood base flange to seat on the top of the 100 diaphragm; the pipe branches being preferably cut to the right length to accomplish the result noted when a standard diaphragm is used. After these parts have been adjusted, a hood is placed over the end of each pipe 105 branch, with the baffle plate 17 preferably directed outwardly, in order that the flame may be directed against the side of the fire pot. When the burners are lighted, the flame, which is usually discharged under considerable pressure, contacts with the baffle 110 plate 17 and spreads, giving all of the fuel

particles an opportunity to ignite, and in that way securing much better combustion than could be had should the fuel be discharged directly into the fire pot. By providing the grate with the diaphragm 13, the cold air is prevented from entering through the bottom of the grate, so that substantially all the air coming into the fire pot must enter through the mixing chambers and fuel pipes, thereby securing a better combustion of the fuel, and a more intense heat.

While I have described my invention as applied to a hot air furnace, its adaptability for use under boilers, or with steam and hot water furnaces is obvious.

Having thus described my invention, what I claim as new therein and desire to secure by Letters Patent is:—

1. In a gas heating apparatus, a fuel feed pipe having a discharge port, a hood seated on said pipe over said port and provided with a fuel opening, and a plate integral with said hood extending upwardly and laterally over said fuel opening, for the purpose set forth.

2. In a gas heating apparatus, a fuel feed pipe having an interior channel and provided with a discharge port, a hood loosely seated on said pipe over said port and provided with a fuel opening of less diameter than the pipe channel, and a plate extending upwardly and laterally over said fuel opening, for the purpose set forth.

3. The combination with a fuel feed pipe, of a hood comprising a channeled body portion adapted to seat over said pipe and a closed end by which said body is supported on said pipe, said end portion having an opening of less diameter than the pipe channel, and a laterally flaring plate projecting from the side of said hood over the hood opening, substantially as set forth.

In testimony whereof I affix my signature in presence of two witnesses.

THOMAS B. JARVIES.
